UNITED STATES PATENT OFFICE.

WILLIAM W. STETTLER, OF ALLENTOWN, PENNSYLVANIA.

LEVEL AND PLUMB-RULE.

No. 895,311.

Specification of Letters Patent.

Patented Aug. 4, 1908.

Application filed March 16, 1907. Serial No. 362,716.

To all whom it may concern:

Be it known that I, WILLIAM W. STETTLER, a citizen of the United States, residing at Allentown, in the county of Lehigh and State of Pennsylvania, have invented a new and useful Improvement in Levels and Plumb-Rules, of which the following is a specification.

This invention relates to spirit levels and more particularly to combined spirit level, plumb and rule; the object being to provide the instrument with adjustable vials so that by setting the vial to the rise or fall desired, a pavement, pipe, bridge or any other kind of work can be readily graded.

With this and other objects in view, the invention consists in the novel features of construction, combination and arrangement of parts hereinafter fully described and pointed out in the claims.

In the drawing forming a part of this specification: Figure 1 is a side elevational view of my improved level. Fig. 2 is a section taken on the lines 2—2 of Fig. 1. Fig. 3 is an enlarged view of a portion of the level. Fig. 4 is a side view of the vial holding member. Fig. 5 is a perspective view of the dial plate. Fig. 6 is a detail sectional view showing the manner of securing the cord carrying the bob.

In the drawings A indicates a stock which may be of any length desired, provided with a central leveling opening A' and a plumbing opening A² adjacent one end, both of which are provided with inwardly projecting portions, to which my improved leveling mechanism is secured, the description of one being sufficient for both as they are formed exactly alike.

Secured in the opening to the sides of the inwardly projecting portion by screws, are dial plates B, which are divided into sixteen equal divisions from right to left, which indicates the rise and fall of one eighth of an inch, for every running foot of the stock as will be hereinafter fully described.

A screw C extends through an opening in each of the plates into the inwardly projecting portion on which is mounted a plate C' provided with a bifurcated upper end forming arms C² which are bent around the ordinary spirit vial D, which securely holds it in place and at the same time allowing it to be readily seen from below when using the level over the head.

A curved slot C³ is formed in the plate

through which extends a set-screw E working through an opening into the inwardly projecting portion of the stock so that the plate can be secured in any position desired by tightening the screw. Secured on the lower end of the plate by a thumb-screw F is a pointer F working over the graduations of the dial so that by setting the pointer for instance to one-fourth in a four-foot stock, the rise and fall would be one inch in four feet or if set to one and a half inch, the rise would be six inches in four feet.

One end of the stock is reduced by rabbeting the sides and cutting the corners off obliquely, over which is secured a cap H, the walls of which are provided with oppositely disposed slots H' in which the end of the plumb cord I is adapted to be secured by pulling the cord through the same, until the knot at the end of the cord engages the end of the cap, and securely holds it in position. The cord extends downward through a slot in the head of a screw J secured in the stock having a bob at its lower end, said screw serving to hold the weight out from the stock. It will be readily seen that if each of the vials should become broken a plumb and bob could be readily attached and used until the vial could be replaced.

Having thus fully described my invention, what I claim as new and desire to secure by Letters Patent is:—

1. In a device of the kind described, the combination with a stock provided with an opening having an inwardly projecting portion, of a dial secured in said opening over said inwardly projecting portion, and provided with spaced openings, a screw extending through one of said openings into the stock, a plate pivotally mounted on said screw and provided with a curved slot, a set-screw extending through said slot in said plate, and through another of said openings in said dial into said stock for holding in adjustment said plate, said plate having a bifurcated upper end forming arms, a spirit vial carried by said arms and secured in said arms by bending the arms around the vial, and a pointer detachably secured on the lower end of said plate working over the graduations of the dial, for the purpose described.

2. In a device of the kind described, the combination with a stock provided with transverse and longitudinal leveling and

895,311

plumbing openings, having inwardly projecting portions, of graduated dials secured to said portions, plates pivotally mounted on said dials provided with slots, screws secured 5 in said dials extending through said slots, arms projecting upwardly from said plates carrying vials, and pointers mounted on said

plates working over the graduations of the dials for the purpose described.

WILLIAM W. STETTLER.
